UNITED STATES PATENT OFFICE.

RAY COWLES, OF SAN FRANCISCO, CALIFORNIA.

ROTARY MULTICYLINDER ENGINE.

1,245,443.

Specification of Letters Patent.

Patented Nov. 6, 1917.

Application filed May 20, 1916. Serial No. 98,807.

To all whom it may concern:

Be it known that I, RAY COWLES, a citizen of the United States, residing at the city and county of San Francisco and State 5 of California, have invented new and useful Improvements in Rotary Multicylinder Engines, of which the following is a specification.

This invention relates to a rotary multi- 10 cylinder engine.

The object of the present invention is to provide a simple, substantial four-cycle internal combustion engine of the multi-cylinder rotary type, which embodies a novel cylinder mounting, valve mechanism, piston and fly-wheel connection, ignition mechanism and other details of construction hereinafter to be more fully described, having reference to the accompanying drawings in 20 which—

Figure 1 is a side elevation of the engine.

Fig. 2 is a central sectional view of same.

Fig. 3 is an end view of the engine, partly in section.

Fig. 4 is a side elevation of the valve, partly in section.

Fig. 5 is an enlarged detail view of the inner cylinder ends, valve and gearing connection.

Fig. 6 is a longitudinal section through the shaft, valve and inner cylinder ends.

Fig. 7 is an enlarged cross-section of the valve.

Referring to the drawings in detail, A 35 indicates the stationary crank shaft; 2 the webs of the shaft, and 3 the crank pin. Mounted to rotate about the crank pin is a hub member 4, which in this instance serves as a multi-cylinder head, a valve casing and 40 a bearing for the cylinders generally indicated at 5, 6 and 7. Turnably mounted interior of the hub member 4, and independent of same, is a cone-shaped rotary valve 8. This valve is provided with an inlet port 9, 45 which communicates with a hollow crank pin 3, and an exhaust port 10. The valve proper is rotated at the ratio of one and a half to one revolution of the cylinders and this is accomplished by means of a set of 50 external and internal gears shown in Figs. 5 and 6. These gears are arranged as follows: An internal gear such as indicated at 11 is secured to the hub 4. Intermeshing with said gear is an external gear 12, and

formed integral with the gear 12 is a third 55 gear 13, which intermeshes with an external pinion 14 secured on the rotary valve. The gears 12 and 13 form intermediate idlers between the gears 11 and 14 and as the gear 11 is provided with 96 teeth and the gear 14 with 64 teeth, it can easily be seen that the ratio between gears 11 and 14 will be one and one-half to one; that is, one revolution of gear 11 which turns with the hub 4 and connected cylinders 5, 6 and 7 will cause 65 one and one-half revolutions to be transmitted to the gear 14 with the attached rotary valve. Formed in the hub member are three radially disposed ports 15, 16 and 17 and formed in the hub in alinement with 70 each of said ports is a pair of exhaust ports 18 and 19.

Gas to support combustion is admitted to each individual cylinder in the following manner: Referring to Figs. 3 and 6, it will 75 be seen that one end of the crank shaft is hollow, as indicated at 20, and that the adjacent web is hollowed out as at 21, to form communication between the shaft 20 and the hollow crank pin 3. The shaft 20, webs 2 80 and pin 3, are stationary as before described, and the shaft end 20 may be connected with any suitable form of carburetor not here shown. The gas supplied by the carburetor passes through the shaft 20 and 85 the hollow crank pin 3, then out through a plurality of radially disposed ports 22, see Fig. 6, into an annular chamber 23, formed between the crank pin and the rotary valve. This chamber is formed by a centrally disposed sleeve 24 secured interior of the valve and spaced from the crank pin by means of 90 a pair of bearing bushings 25. The sleeve proper is secured in the valve and will therefore turn with same and as it is provided with a port 26 positioned in alinement with the inlet port 9, it can be seen that the gas will escape from the annular chamber into the inlet port 9 and will here enter the cylinders through the radially disposed ports 15, 16 or 100 17, when a correctly timed piston is moving outward with relation to its adjacent cylinder head or hub member 4.

Mounted on each end of the crank shaft A, adjacent the webs 2, is a pair of anti-friction 105 bearings 27 and 28. These bearings are provided for the purpose of supporting the fly-wheel generally indicated at 30. This fly-

wheel is channel shaped in cross section and is supported with relation to the bearings 27 and 28 by means of a plurality of radially disposed tubular spokes 31. The fly-wheel proper is concentrically positioned with relation to the crank shaft 8, while the cylinders and connected hub 4 are eccentrically positioned. This construction permits each individual piston member to be connected with the rim of the fly-wheel as indicated at 32, and furthermore, permits each individual cylinder to be connected with the fly-wheel rim by means of an extension 33 and a crank arm 34. Each extension 33 and crank 34, serves the function of a master-connecting rod, that is, it permits freedom of movement between the cylinders and fly-wheel but will, at the same time, maintain a fixed relation between same during each revolution.

The present illustration of the engine shows a valve movement which permits a four-cycle principle of operation. This can be understood when it is taken into consideration that the valve proper will rotate three revolutions while the connected cylinders revolve two. The exhaust and inlet passages formed in the valve will thus pass each cylinder port 15, 16 and 17 once during every two revolutions of the cylinders and will therefore permit the four-cycle function to take place with relation to each cylinder, that is, the inlet port will be in register with port 15 while the co-operating piston is traveling outwardly. The piston will then move in and compress the charge. A spark plug generally indicated at 40, carried by the valve, will next move into communication with port 15 and fire the charge. The piston will then travel outwardly and the valve will in the meantime have rotated to a position where the exhaust passage moves into register to permit the piston to again travel inwardly and scavenge the burnt charge.

The gas scavenged by the inward movement of the piston passes through the radial port 15 and then out through the connected exhaust port and the aligned ports 18 and 19 previously described, direct to the atmosphere.

It will be noticed by referring to Figs. 2 and 3, that the force of each explosion is exerted to drive the pistons in an outward direction and not to drive them inwardly, as is usually the case. This is one of the important features of the present invention as the blow or shock exerted by each explosion is distributed to the periphery of the fly-wheel and the widely separated bearings 27 and 28 and partly against the hub bearing or crank pin 3. In other words, a large bearing area is provided to absorb the shock of each explosion and advantage is furthermore taken, of the fact that the power gen-

erated is exerted on the same line as the centrifugal action of the revolving parts, permitting loose or worn connecting rod pin bushings to operate without noise or vibration.

The engine constructed as here shown, is particularly adapted for aviation purposes as the comparatively high revolving speed of the cylinders and fly-wheel provides ideal conditions for air cooling. Each cylinder is therefore ribbed as shown and the central hub is similarly cored out and ribbed whenever possible, to permit a free circulation of air through and around same. The rotary valve proper is furthermore provided with a plurality of longitudinally disposed parallel passages 42 to permit cooling of same. One end of each of these passages communicates with a hollow chamber 43, formed in the bearing cap 44, while the opposite end of each passage communicates with a port 45 opening through the hub proper and as the bearing cap is provided with a plurality of radially disposed ports 46, it can easily be seen that centrifugal action will cause a comparatively free circulation of air through the passages, thus keeping the valve cool. The valve is furthermore cooled by the incoming gases passing through the radial ports 22 in the crank pin and the communicating inlet port; the accumulated wind pressure in flight on air craft will also cause vigorous circulation of cold air through the valve passages. Further cooling is obtained by annular ribs formed on the valve sleeve. 100

One of the passages, preferably the central one, is provided for the reception of the spark plug 40. This plug is connected through a wire 50 with a brush and commutator ring, generally indicated at 51. This is in turn connected with any suitable form of electric source of supply and timing mechanism not here shown. A spark plug mounted in a valve of the character here shown forms another important feature of the present invention as it provides a more efficient ignition than could otherwise be secured. This will be more readily understood when it is stated that the current passes through the plug during the whole period that the plug is in communication with the port 15. In other words, a hot spark is moved across the port opening, thus igniting a comparatively larger body of gas than would otherwise be possible. Another 110

important feature obtained in connection with this method of ignition is a uniform timing of each explosive charge, that is, each explosive charge is ignited at precisely the same time or at the right moment, thus providing uniformity of timing and ignition and positively preventing vibrations set up by variations in timing. It can furthermore be seen that only one spark plug will be required and that the system is not likely to 120

get out of order as the only moving parts needed in connection with same would be a single vibrator or some similar mechanism.

While a three cylinder engine is here shown and a cone valve, it is obvious that any suitable number of cylinders may be employed and that puppet valves operated by a cam sleeve may be used, if desired.

Another important feature of the present invention is the simplicity of the lubricating system. A pipe 60 connected with a suitable source of supply enters the hollow shaft end 20 and delivers oil to the revolving anti-friction bearing 27. The oil then passes out through one or more of the hollow spokes 31, which connect with the connecting rod pins indicated at 61. These pins are hollow and the connecting rods are similarly hollowed-out as indicated at 62, to permit the oil to be forced inwardly to the piston wrist pins 63. The oil then passes out through said pins to the cylinders and is naturally forced in an outward direction by the centrifugal force produced by the high revolving speed. A cap 64 placed in the outer end of each cylinder however, prevents the oil from freely discharging and therefore serves as a trap or collector, which permits the oil to be returned to either bearing 80 or 81 through pipes 80^a and 81^a. The inner end of each cap 64 projects partway into the cylinders and cooperates with the end of the piston to form a pump which has sufficient pressure behind it to force the oil back to the bearings against the centrifugal action produced. Another pipe 65 entering through either crank shaft and crank pin lubricates the conical valve face and the surplus is collected by channels and distributed to the radially disposed pipes generally indicated at 70, see Figs. 1 and 2. The outer ends of these pipes enter the cylinders at right angles to the piston wrist pins and therefore lubricates the pistons on the sides opposite to the wrist pin ends. A four-point lubrication in connection with each cylinder and piston is thus provided. All lubricating oil admitted will discharge outwardly, due to centrifugal action and it will therefore be impossible for oil to enter the ports 15, 16 and 17 and foul the spark plug carried by the valve. Carbonization by lubrication is thus prevented and ignition troubles of this character positively prevented.

The materials and finish of the several parts of the invention may be such as the judgment and experience of the manufacturer may dictate.

I wish it understood that various changes in form, proportions and minor details of construction may be resorted to within the scope of the appended claims, and that I do not wish to limit myself to the specific design and construction here shown.

Having thus described my invention, what

I claim and desire to secure by Letters Patent is—

1. In a rotary multi-cylinder internal combustion engine, a stationary crank shaft, a fly-wheel journaled on the shaft, a hub member journaled on the crank pin of the shaft, a plurality of radially disposed cylinders secured to the hub member, said hub member being provided with radially disposed ports communicating with each cylinder, a crank connection between each cylinder and the fly-wheel, a connecting rod connecting each cylinder piston with the fly-wheel, a rotary valve having an exhaust and inlet port formed therein interposed between the crank pin and the ported hub, a gear secured on the hub, a second gear secured on the valve, a pair of intermediate gears interposed between said first and last named gears, adapted to maintain a speed ratio of one and one-half revolutions of the valve to one revolution of the hub, and means for admitting an explosive mixture to the inlet port of the valve.

2. In a rotary multi-cylinder internal combustion engine, a stationary crank shaft, a fly-wheel journaled on the shaft, a hub member journaled on the crank pin of the shaft, a plurality of radially disposed cylinders secured to the hub member, said hub member being provided with radially disposed ports communicating with each cylinder, a crank connection between each cylinder and the fly-wheel, a connecting rod connecting each cylinder piston with the fly-wheel, a rotary valve having an exhaust and inlet port formed therein interposed between the crank pin and the ported hub, a gear secured on the hub, a second gear secured on the valve, a pair of intermediate gears interposed between said first and last named gears, adapted to maintain a speed ratio of one and one-half revolutions of the valve to one revolution of the hub, and means for admitting an explosive mixture to the inlet port of the valve and a spark plug carried by the valve adapted to rotate with the valve.

3. In a rotary multi-cylinder engine, a shaft, a hub member journaled thereon and provided with a plurality of radial ports opening through its periphery and an exhaust port also extending radially on opposite sides of each first port but opening through the adjacent end face of the hub member, a radially disposed cylinder mounted on the hub member over each first port thereof, pistons operable in the cylinders, and a valve interposed between the shaft and hub member having a longitudinally arranged exhaust port adapted for communicating at its ends with the exhaust ports of the hub member and intermediate its ends with the first ports.

4. In a rotary engine, a shaft, an air

jacketed valve thereon having its jacket opened to the atmosphere at both ends, and a ported cylinder revoluble about the shaft and valve.

5. In a rotary engine, a stationary crank shaft, a fly wheel journaled on the shaft, a hub member journaled on the crank pin of the shaft, a cylinder extending outwardly therefrom, said hub member being provided with a port leading into the cylinder and a second port leading to the atmosphere, a piston in the cylinder connected to the fly-wheel, a crank connection between the latter and the cylinder, and a rotary valve about which the hub member revolves, said valve having an inlet port adapted for communication with the first port of the hub member and an outlet port adapted to connect the two hub member ports.
10. In a rotary engine, a stationary crank shaft, a fly-wheel journaled on the shaft, a hub member journaled on the crank pin of the shaft, a cylinder extending outwardly therefrom, said hub member being provided with a port leading into the cylinder and a second port leading to the atmosphere, a piston in the cylinder connected to the fly-wheel, a crank connection between the latter and the cylinder, and a rotary valve about which the hub member revolves, said valve having an inlet port adapted for communicating with the first port of the hub member and an outlet port adapted to connect the two hub member ports, and a spark plug carried
15. by the valve for igniting the gas in the cylinder through the first port of the hub member.
7. In a rotary multi-cylinder engine, a crank shaft, a hub member journaled thereon, a plurality of radially disposed cylinders fixed on the hub member, the latter having radial ports communicating with the cylinders, pistons in the cylinders connected for imparting rotary movement thereto, a rotary valve interposed between the shaft and hub member and provided with an air jacket having spiral passages opened to the atmosphere, and a sparkler arranged in one of the spiral passages and opening through the periphery of the valve for communicating with the cylinders through the hub ports.
20. In a rotary engine, a stationary crank shaft, a fly-wheel journaled on the shaft, a hub member journaled on the crank pin of the shaft, a cylinder extending outwardly therefrom, said hub member being provided with a port leading into the cylinder and a second port leading to the atmosphere, a piston in the cylinder connected to the fly-wheel, a crank connection between the latter and the cylinder, a rotary valve about which the hub member revolves, said valve having an inlet port adapted for communicating with the first port of the hub member and an outlet port adapted to connect the two hub member ports, and a spark plug carried
25. by the valve for igniting the gas in the cylinder through the first port of the hub member.
8. In a rotary engine, a hollow ported shaft, a ported cylinder revoluble thereabout, and an interposed valve having an

air jacket formed with spiral passages and opened to the atmosphere at both ends.

9. In a rotary engine, a hollow ported shaft, a ported cylinder revoluble thereabout, and an interposed valve having an air jacket formed with spiral passages.

10. In a rotary multi-cylinder engine, a crank shaft, a hub member journaled thereon, a plurality of radially disposed cylinders fixed on the hub member, the latter having radial ports communicating with the cylinders, pistons in the cylinders connected for imparting rotary movement thereto, a rotary valve interposed between the shaft and hub member and provided with an air jacket having spiral passages opened to the atmosphere, a sparkler arranged in one of the spiral passages and opening through the periphery of the valve for communicating with the cylinders through the hub ports, a commutator ring on the crank shaft connected to a source of electrical energy, and a brush wiping the ring and connected to the sparkler.

11. In a rotary engine, a ported crank shaft, a sleeve surrounding the ported shaft and having annular passages leading to a peripheral port, a valve receiving the sleeve and provided with a port registering with the sleeve port, multi-cylinder means rotatable about the valve, a driving connection between the means and the valve for rotating the latter, and piston means operable in the cylinders.

12. In a rotary multi-cylinder engine, a shaft, a hub member journaled thereon and provided with a plurality of radial ports opening through its periphery, a cylinder disposed radially on the hub member over each port, pistons operable in cylinders, and a valve interposed between the shaft and hub member and provided with a port for communicating with the hub port, said valve port being formed longitudinally of the valve and opening at both ends into the atmosphere.

In testimony whereof I have hereunto set my hand in the presence of two subscribing witnesses.

RAY COWLES.
